COMBER HALF-LAP

James C. Wilson and Richard Ferguson, Charlotte, N. C., assignors to The Terrell Machine Company, a corporation of North Carolina

Application December 27, 1950, Serial No. 202,922

16 Claims. (Cl. 19—116)

1

This invention relates to comber half-laps, and more particularly to an improved arrangement of needle bars for forming half-lap comb segments.

As is well known, comber half-laps comprise a body member formed with hubs on which the half-lap may be mounted for rotation during the combing operation, and further formed with an arcuate mounting surface in relation to which a series of needle bars that carry projecting needles are secured to form a comb segment for action during a portion of each revolution of the half-lap on the fiber being combed.

The construction of comber half-laps has heretofore characteristically involved troublesome difficulty in the proper arrangement of the needle bars on the arcuate mounting surface of the half-lap body member. It is common practice to arrange the needle bars in graduated sizes on the arcuate mounting surface, or in some cases to form the mounting surface about a center that is eccentric to the center on which the half-lap rotates, so that needles becoming progressively finer from the leading needle bar may be disposed on the needle bars with a decreasing projection to compensate for loss of strength as their fineness increases, while still maintaining all of the needle tips in a common arc about the center of rotation of the half-lap as required for fully effective combing action.

Such an arrangement makes it necessary to provide for very precise location of the needle bars in securing them in relation to the arcuate mounting surface of the half-lap body. A frequently employed procedure is to form individual grooves for the needle bars in the arcuate mounting surface and then fit and secure each needle bar separately in these grooves. In other instances, the needle bars have been individually secured directly to the face of the arcuate mounting surface, but any procedure for individual fastening of the needle bars, however accomplished, necessarily involves an extensive amount of machining and much tedious assembly work.

In order to avoid these objectionable features of the usual methods for mounting the needle bars individually, it has been proposed to form the needle bars with wedge shaped base portions having side faces intended to lie in radial planes with respect to the arcuate mounting surface of the half-lap, and to provide means for clamping these needle bars as a group on the mounting surface. Such prior proposals have not proved satisfactory, however, because of the practical

difficulty encountered in conforming a group of needle bars of this sort to the arcuate form of the mounting surface due to the fact that any deviation at all of the needle bar side faces from a radial plane, even such variations as normally occur within practical manufacturing tolerances, can accumulate as the needle bars are grouped to cause a substantial divergence in the group as a whole from the arcuate mounting surface and thus prevent the necessary precise location of the needle bars in relation to this mounting surface.

According to the present invention there is now provided a form of needle bar which is uniquely adapted for interfitting in groups to form composite comb segments that may be readily secured in accurate conformance on the arcuate mounting surface of a half-lap. Briefly described, the needle bar of the present invention is characterized by a base portion having opposite, non-planar, side faces that are shaped with profiles described about circular arcs (i. e., profiles coinciding with circumscribed around, or inscribed within circular arcs). When needle bars formed in this manner are assembled as a group by interfitting at the side faces of their base portions to form a comb segment, they will always find a proper interfitted relation in conformance with the mounting surface of a half-lap to which they are secured despite any slight variations that may occur in shaping the side faces, and may thus be assembled and mounted in place with great facility. In addition, the proper interfitted relation found by the needle bars upon assembly and mounting as a composite comb segment will also result in disposing each needle bar with a uniform angularity in relation to the half-lap mounting surface.

These and other features of the present invention are described in detail below in connection with the accompanying drawings, in which:

Fig. 1 is a perspective view of a comber half-lap embodying the invention;

Fig. 2 is a sectional detail taken substantially on the line 2—2 in Fig. 1;

Fig. 3 is an enlarged detail taken mainly in section on the line 3—3 in Fig. 1;

Fig. 4 is a side elevation of one of the needle bars shown in Figs. 1 and 3;

Fig. 5 is an enlarged right end elevation of the needle bar shown in Fig. 4;

Fig. 6 is an enlarged detail corresponding generally to Fig. 3, but illustrating a further embodiment of the invention incorporating a modified form of needle bar;

Fig. 7 is a side elevation of one of the needle bars shown in Fig. 6; and

Fig. 8 is an enlarged right end elevation of the needle bar shown in Fig. 7.

Referring now in detail to the drawings, and more particularly at first to Fig. 1, a comber half-lap constructed in accordance with the present invention is indicated generally by the reference numeral 10 and, as shown, comprises a body member 12 fitted with a usual form of mounting hubs 14 and presenting an arcuate mounting surface as at 16 on which a series of needle bars 18 may be grouped to constitute a comb segment.

In the half-lap construction of the present invention, the body member 12 is assembled with the mounting hubs 14 (as illustrated best in Fig. 2) so that the center about which the arcuate needle bar mounting surface 16 is formed, as indicated at 20, is disposed eccentrically with respect to the center 22 of the mounting hubs 14 about which the half-lap 10 rotates. This eccentric arrangement is obtained by providing a shim member 24 to position the body member 12 off-center in relation to the mounting hubs 14 when these elements are assembled by suitable fastening means such as the screws 26. Accordingly, by proportioning the shim member 24 properly, needle bars 18 of identical size may be employed in forming the entire comb segment of the half-lap 10 while still allowing the use of needles of increasing fineness from the leading needle bar, as has been mentioned previously, and will be pointed out more in detail presently.

The manner in which the needle bars 18 are arranged to form the comb segment of the half-lap 10, according to one representative embodiment of the invention, is illustrated in Fig. 3 of the drawings, and the form of the individual needle bars 18 employed in this embodiment is illustrated in further detail in Figs. 4 and 5. Each of the needle bars 18 comprises generally a needle carrying portion 28, and a base portion 30 which is particularly adapted, as already noted above, for interfitting in the course of assembling a group of the needle bars 18 as a composite comb segment.

In the embodiment illustrated in Figs. 3, 4 and 5, the interfitting base portions 30 of the needle bars 18 are of cylindrical form with a groove 32 formed in one side face about a circular arc having the same radius as the cylindrical form of the base portion 30. As a result, this groove 32 at one side face of each base portion 30 is adapted for interfitting over the entire cylindrical surface forming the other side face of the base portion 30 of any other needle bar 18, and it should also be noted that the cylindrical form of the base portions 30 further adapts them for line contact with the arcuate mounting surface 16. By virtue of this arrangement, when a group of the needle bars 18 are assembled with the side faces of their base portions 30 interfitted, they are disposed for relative shifting at these side faces so that they may be conformed as a group with any arcuate surface that will support them; and because the base portions 30 are adapted for line contact with the supporting arcuate surface, the relative shifting necessary to find a proper interfitted relation in conformance with this arcuate surface may be determined simply by bottoming the base portions 30 on the surface.

Proper interfitting of the needle bars 18 in this manner may be obtained readily as a practical matter, too, because the interfitting of the base portions 30 at side faces which are formed about

circular arcs in accordance with the present invention is not perceptibly affected by dimensional variations within the range of usual manufacturing tolerances. Also, the interfitting of the needle bars 18 in this manner so that their proper interfitted relation is determined by contact of the base portions 30 with the supporting arcuate surface has the further effect of disposing each of the needle bars 18 with their upper needle carrying portions 28 extending at a uniform angularity from the arcuate surface and therefore regularly spaced. Accordingly, by providing means for clamping a group of the needle bars 18 sidewise in interfitted relation and for forcing their base portions 30 into contact with the arcuate mounting surface 16 of the half-lap 10, the needle bars 18 may be readily disposed as a comb segment conforming exactly with the arcuate mounting surface 16, and having the needle carrying portions 28 extending with a uniform angularity so that they are regularly spaced at the working face of the comb segment.

The needle bars 18 may be assembled suitably for mounting in the manner just described above by means of tie rods 34 adapted to be extended through registering apertures 36 formed in each needle bar 18, the apertures 36 being formed for a loose fit on the tie rods 34 so as to provide adequate clearance for permitting the needle bar base portions 30 to shift as necessary in finding their proper interfitted relation. The tie rods 34 are preferably provided as a solid bolt-like rod, as shown in Fig. 3, having a curvature corresponding generally to the arcuate form of the mounting surface 16, and having sufficient flexibility for forcing the needle bar base portions 30 into contact with the mounting surface 16. However, other types of tie rod means, such as stranded wire cable, for example, might be used, and means other than the apertures 36 might be provided for engaging the needle bars 18 with the tie rod means, if desired.

In using tie rods 34 such as are illustrated in Fig. 3 to assemble the needle bars 18 for mounting, each tie rod 34 is threaded at its ends to receive nuts as at 38 and 40 that may be turned down on clamping bars 42 and 44 arranged for exerting sidewise pressure on the interposed group of needle bars 18 and thereby clamp them in interfitted relation. The clamping bars 42 and 44 also serve as means for securing the assembled needle bars 18 on the arcuate mounting surface 16, the clamping bar 42 being adapted for engagement directly by mounting screws as at 46, and the clamping bar 44 being formed with elongated slots as indicated by dotted lines at 48 in Fig. 3 to receive fastening bolts as at 50 so that it may be positioned for sidewise clamping of the needle bars 18 as they are mounted on the arcuate surface 16. The tie rod nuts 40 and the fastening bolts 50 may thus be finally tightened in turn to clamp the base portions 30 of the needle bars 18 in interfitted relation and force each of them to a position resting on the arcuate mounting surface 16.

The representation in Fig. 3 of the needle bar apertures 36 in the finally clamped position of the needle bars 18 has been purposely exaggerated to emphasize the freedom allowed for the needle bars to find a proper interfitted relation as they are clamped in place. Actually these apertures 36 would in the usual case be disposed in substantial alignment with each aperture 36 arranged tangent to an arc concentric with the arc of the tie rods 34 and thereby form a continuous passageway to receive the tie rods 34.

The fact that the arrangement of the present invention results in a uniform angular disposition of the needle bars 18 on the mounting surface 16, as already mentioned above, allows the needle carrying portions 28 of the needle bars 18 to be shaped for presenting a substantially continuous surface at the face of the comb segment formed by the needle bars 18. These needle carrying portions 28 are formed to provide a needle mounting face 52 on which combing needles as at 54 may be secured, and an opposite face 56 arranged to extend closely adjacent the needles 54 secured on an adjoining needle bar 18. No attempt has been made in Fig. 3 to illustrate the increasing fineness of the needles 54 on the successive needle bars 18 from the leading one (as seen at the left in Fig. 3), although it will be noted that the needles 54 are shown with a decreasing projection to compensate for loss of strength as their fineness increases; and with all of the tips of the needles 54 disposed in a common arc about the center of rotation 22 of the half-lap 10 as is required in half-lap construction.

By providing for this decreasing projection by the eccentric arrangement of the arcuate mounting surface 16, the needle bars 18 may be employed in identical sizes to form the comb segment for the half-lap 10, thus simplifying the half-lap construction substantially so that important advantages are provided both in assembly and repair of half-laps constructed in accordance with the present invention. For example, the uniform size of needle bar 18 makes it possible to use a standard jig for holding the needle bars as they are needled, and the only adjustment necessary during the needling operation is the disposition of the needles 54 at a proper degree of projection in accordance with their fineness, as they are secured on the needle mounting face 52. In addition, it will usually be desirable to relieve the opposite faces 56 of the needle carrying portions 28 selectively in accordance with the size of needle 54 carried by the needle bar 18 to which they will be adjacent, so that these opposite faces 56 of each needle bar 18 will not touch, but will extend as closely contiguous as practical to the needles carried by the adjoining needle bar 18. This relief of the opposite needle bar 56, however, may be easily provided for according to the fineness of the needles.

With further reference to the form of needle bar base portion employed according to the present invention, it should be noted that the base portions 30 illustrated in Figs. 3, 4 and 5, and described above, are only representative and that the same advantages can be obtained by shaping the needle bar base portions in other ways as long as provision is made for allowing them to find a proper interfitted relation about circular arcs. For this purpose, it is only necessary that one of each pair of mating faces on adjacent needle bars be formed with a contact face that is cylindrical (i.e., coincides in profile with a circular arc), or is at least cylindrical at two spaced contact areas for mating with the other face with which it is paired, and that the contact area of the needle bar base portion with the arcuate mounting surface be likewise cylindrical to provide for line contact as noted above. In the base portions 30 described above, both of the mating faces are cylindrical, but this does not have to be so as is illustrated by the embodiment shown in Figs. 6, 7 and 8 of the drawings

in which a half-lap 100 is shown incorporating a modified form of needle bar 102 as a further embodiment of the invention.

In Fig. 6, the half-lap body member is shown at 104 fitted eccentrically about a center 106 on mounting hubs 108 having a center 110 about which the half-lap 100 rotates. The eccentric mounting of the body member 104 is accomplished by means of a shim member 112 as in the previously described embodiment, and presents an arcuate mounting surface 114 on which the needle bars 102 are clamped by tie rods 116 fitted at each end with nuts 118 to exert sidewise pressure on the needle bars 102 through clamping bars 120 and 122, which are arranged to be secured to the body member 104 by means of screws as at 124 and fastening bolts 126 extending through elongated slots 128 in the clamping bar 122. It may be noted in passing that whereas the comb segment of the previously described half-lap 10 shown in Fig. 3 contains seventeen needle bars 18, the comb segment for the half-lap 100 shown in Fig. 6 is composed of only sixteen needle bars 102, a spacer bar 132' having the same form as the base portion of the needle bars 102 being employed adjacent the clamping bar 120 to provide adequate clearance for manipulation of the nuts 118. The number of needle bars constituting the half-lap comb segments might of course be varied further as desired, and the spacing bar 132' in Fig. 6 illustrates how elements corresponding in form to the needle bar base portions alone may be used in the comb segments too for spacing the needle bars whenever necessary or desired.

The individual form of the needle bars 102 employed in the embodiment of the invention illustrated in Fig. 6 is shown in further detail in Figs. 7 and 8 of the drawing. Here again the needle bars 102 comprise needle carrying portions 130 and base portions 132. The base portions 132 in this case are also cylindrical in form, but instead of having a cylindrical groove formed in one side face thereof, they are provided with a dihedral or V-shaped groove 134 having faces which lie tangent to a circular arc of the same radius as the cylindrical form of the base portion 132. As a result, the grooves 134 are adapted for interfitting with the cylindrical form of an adjacent needle bar base portion 132 in exactly the same manner as in the previous embodiment described above, and are adapted to find a proper interfitted relation in exactly the same manner too. Also, it will be noted that the needle bars 102 in this embodiment are of somewhat simpler form than the needle bars 18 of the previous embodiment described above, and a particular advantage of this simplified form of the needle bars 102 is that it allows the use of a plane face 65 extending from the groove 134 to form the needle mounting face 136 of the needle carrying portion 130 and thereby provides considerably more convenient access in the course of securing needles 130 on this mounting face 136.

It would also be possible to form needle bars according to the present invention with a groove that was cylindrical in form at the inner face of the base portions and with an outer face having a polygonal form inscribed within a circular arc having the same radius as the cylindrical groove, or the needle bar base portions might be formed so that they were alternately of entirely cylindrical form for interfitting with interposed needle bars having base portion with grooves described about circular arcs in both faces. Again, it

would be possible to employ the present invention to advantage in constructing a half-lap of the type in which the arcuate mounting surface is concentric with the axis of rotation of the half-lap, by employing needle bars of increasing size to provide for decreasing projection of the needles as they became finer, in which the mating faces of the needle bar base portions might still be of uniform size from needle bar to needle bar with the projecting length of the needle carrying portion progressively increasing, or in which the pairs of mating surface might increase in size as the size of the needle bars increased. Any of these and other arrangements are possible and might be used to advantage in particular instances, although the embodiments illustrated in the drawings and described above are believed to be most practical under usual circumstances.

The present invention has been described in detail above for purposes of illustration only, and is not intended to be limited by this description or otherwise except as defined in the appended claims.

We claim:

1. A comber half-lap comprising a half-lap body member formed with an arcuate needle bar mounting surface, and a plurality of needle bars assembled as a composite comb segment and secured on said mounting surface, said needle bars being formed with interfitting base portions having opposite, non-planar, side faces shaped with profiles described about circular arcs, whereby the base portions of said needle bars find a proper interfitted relation when secured on said arcuate mounting surface.

2. A comber half-lap comprising a half-lap body member formed with an arcuate needle bar mounting surface, and a plurality of needle bars assembled as a composite comb segment and secured on said mounting surface, said needle bars being formed with interfitting base portions having concave and convex opposite side faces shaped with profiles described about circular arcs of equal radii, whereby the base portions of said needle bars find a proper interfitted relation for conforming said composite comb segment to the arcuate form of said mounting surface when secured in place.

3. A comber half-lap comprising a half-lap body member formed with an arcuate needle bar mounting surface, and a plurality of needle bars assembled as a composite comb segment and secured on said mounting surface, said needle bars being formed with interfitting base portions shaped for line contact with said mounting surface and having concave and convex opposite side faces shaped in profile about circular arcs of equal radii, whereby said needle bars when secured in place find an interfitted relation at said base portions conforming said composite comb segment to the arcuate form of said mounting surface and disposing each needle bar at a uniform angularity in relation to said mounting surface.

4. A comber half-lap comprising a half-lap body member formed with an arcuate needle bar mounting surface, a plurality of needle bars, and means for assembling and securing said needle bars on said arcuate mounting surface as a composite comb segment, said needle bars being formed with base portions having complementary concave and convex opposite side faces whereby the base portions of said needle bars find a proper interfitted relation when secured on said mounting surface.

5. In a comber half-lap having an arcuate needle bar mounting surface, a plurality of needle bars forming a composite comb segment secured on said mounting surface, said needle bars being formed with interfitting base portions having complementary concave and convex opposite side faces, whereby said needle bars find a proper interfitting relation for conforming said composite comb segment to the arcuate form of said mounting surface when secured in place.

15 6. A comber half-lap comprising a half-lap body member formed with an arcuate needle bar mounting surface, and a plurality of needle bars assembled as a composite comb segment and secured on said mounting surface, said needle bars being formed with base portions having opposite side faces, one side face of each needle bar being cylindrical in form and the other side face being shaped for interfitting with the cylindrical form 20 of said first mentioned side face.

7. A comber half-lap comprising a half-lap body member formed with an arcuate needle bar mounting surface, and a plurality of needle bars assembled as a composite comb segment and secured on said mounting surface, each of said needle bars having a base portion of cylindrical profile in one side face of which a V-shaped groove is formed with the faces of said groove lying tangent to a circular arc having the same 30 radius as said cylindrical profile, whereby the base portions of said needle bars are formed for line contact with said mounting surface and for interfitting in conformance with the arcuate form of said mounting surface.

35 8. In a comber half-lap having an arcuate needle bar mounting surface, a plurality of needle bars for forming a composite comb segment when secured on said mounting surface, each of said needle bars having a cylindrical base portion one side face of which is formed with a groove shaped about a circular arc having the same radius as the cylindrical form of said base portion.

40 9. A needle bar for a comber half-lap, said needle bar comprising a base portion and a needle carrying portion extending from said base portion, the base portion of said needle bar being cylindrical in profile and having one side face thereof formed with a groove shaped about a circular arc having the same radius as the cylindrical profile of said base portion, whereby a group of said needle bars may be interfitted at their base portions for assembly as an arcuate comb segment in which the needle carrying portion 55 of each needle bar will find a regularly spaced extending disposition.

45 10. A needle bar as defined in claim 9 and further characterized in that said groove is formed with a V-shape having the faces thereof 60 lying tangent to said circular arc.

11. In a comber half-lap having an arcuate needle bar mounting surface, a plurality of needle bars for forming a composite comb segment, said needle bars being formed with interfitting base portions shaped for line contact with said mounting surface and having concave and convex opposite side faces shaped in profile about circular arcs of equal radii, each of said base portions being further formed with registering apertures extending transversely therethrough in relation to said side faces, and tie rods disposed through said apertures for assembling said needle bars to form said composite comb segment and for securing said comb segment on said mounting surface.

12. A comber half-lap comprising a half-lap body member formed with an arcuate needle bar mounting surface, a plurality of needle bars for forming a composite comb segment, and tie rods arranged for assembling said needle bars to form said comb segment and for securing said comb segment on said mounting surface, said needle bars having interfitting base portions formed with registering apertures extending transversely therethrough for receiving said tie rods, and said base portions being cylindrical in profile and having one side face thereof formed with a groove shaped about a circular arc having the same radius as the cylindrical profile of said base portion, whereby said base portions find an interfitted relation conforming accurately to the arcuate form of said mounting surface when said needle bars are assembled on said tie rods and secured on said surface.

13. A comber half-lap comprising a half-lap body member formed with an arcuate needle bar mounting surface, a plurality of needle bars, and tie rods arranged for assembling said needle bars as a composite comb segment and for securing said comb segment on said mounting surface, said needle bars having base portions formed with registering apertures extending transversely therethrough for receiving said tie rods, and said base portions being cylindrical in profile and having a V-shaped groove formed in one side face thereof with the faces of said groove lying tangent to a circular arc having the same radius as said cylindrical profile, whereby said base portions are formed for line contact with said mounting surface and are adapted for finding an interfitted relation conforming accurately to the arcuate form of said mounting surface when said needle bars are assembled on said tie rods and secured on said surface.

14. A composite comb segment for a comber half-lap, said comb segment comprising a plu-

rality of needle bars each of which is formed with a base portion of cylindrical profile having a groove at one side face thereof that is shaped about a circular arc having the same radius as said profile, and associated means for assembling said needle bars compositely as a comb segment with the base portions thereof interfitted.

15. A composite comb segment for a comber half-lap, said comb segment comprising a plurality of needle bars formed with interfitting base portions having opposite, non-planar, side faces shaped with profiles described about circular arcs, and associated means for assembling said needle bars compositely as a comb segment with the base portions thereof interfitted.

16. A comber half-lap comprising a half-lap body member formed with an arcuate needle bar mounting surface, a plurality of needle bars formed with interfitting base portions having opposite, non-planar, side faces shaped with profiles described about circular arcs, and means for assembling said needle bars with the base portions thereof interfitted and for securing the assembled needle bars on said arcuate mounting surface as a composite comb segment.
